UNITED STATES PATENT OFFICE.

WILLIAM W. ZACKEY, OF PHILADELPHIA, PENNSYLVANIA, ASSIGNOR OF FORTY-NINE
ONE-HUNDREDTHS TO CHARLES B. HEWITT, OF BURLINGTON, NEW JERSEY.

SOUND-BOX ARM FOR TALKING-MACHINES.

1,083,045.

Specification of Letters Patent.

Patented Dec. 30, 1913.

Application filed October 12, 1912. Serial No. 725,447.

To all whom it may concern:

Be it known that I, WILLIAM W. ZACKEY, a citizen of the United States, and residing in the city and county of Philadelphia, 5 State of Pennsylvania, have invented a new and useful Sound-Box Arm for Talking-Machines, of which the following is a specification.

This invention relates to improvements in 10 talking machines and more particularly to the sound amplifying devices and has for an object to provide an amplifying arm and horn which are capable of transmitting and reproducing the sound with a minimum of 15 variation from the original.

It has for a further object to provide a 20 novel means of eliminating the scratching and scraping noises which are produced by movements of the sound arm caused by vibrations of the sound record or irregularities in its surface. To this end I have devised a construction wherein the amplifying arm is maintained substantially in equilibrium, or floating condition, above the record 25 but is so adjusted and arranged as to permit an extremely sensitive action of the needle with respect to the record.

It further consists of other novel features 30 of construction all as will be hereinafter fully set forth.

For the purpose of illustrating my invention, I have shown in the accompanying drawings a preferred embodiment which is at present preferred by me, since the same 35 has been found in practice to give satisfactory and reliable results, although it is to be understood that the various instrumentalities of which my invention consists can be variously arranged and organized and that 40 my invention is not limited to the precise arrangement and organization of these instrumentalities as herein shown and described.

Figure 1 represents a side elevation of a 45 sound reproducing device, embodying my invention, the same being shown partly in section. Fig. 2 represents an enlarged section of a portion of the device. Fig. 3 represents a section on line $x-x$, of Fig. 2. 50 Fig. 4 represents a perspective of the supporting device for the sound arm. Fig. 5

represents a section of a portion of the same. Fig. 6 represents a section of a portion of the sound arm showing its connection to the sound box. Fig. 7 represents a 55 section of a modified form of the device.

Similar numerals of reference indicate corresponding parts in the figures.

Referring to the drawings:—1 designates the sound horn or amplifying device by 60 means of which the sound waves are transmitted from the reproducing mechanism and, in the present instance, this horn is supported on a cross bar 2, or the like, forming a part of the box or receptacle within which 65 or upon which the mechanism is mounted.

3 designates the sound arm which carries on one end thereof a sound box 4 of any well known construction, carrying the customary needle 5, for contact with a record. 70 In the present instance, I have provided a horn tapering or flaring outwardly from the sound box 4, and in order to obtain the desired result in the quality and the volume of the reproduction, I have preferred and 75 have found in practice that an arm which is approximately elliptical in cross section is of the most desirable contour for the desired result.

Attention is directed to the configuration 80 of the horn and arm since a cross section taken at any point in the length of these members will show two substantially parallel surfaces which are joined by curved side surfaces and this construction, as has 85 been found, causes a variation in the sound waves tending to eliminate any scratching or metallic sounds not forming a component part of the reproduced sound.

It will be noted that the smaller end of 90 the arm 3 is joined directly to the sound box 4, and therefore the sound waves are conducted substantially directly from the reproducing diaphragm to the interior of the arm 3, there being but a slight turn or bend 95 as shown at 6, upon one portion of the arm. This construction has the effect of materially reducing the reaction of the sound waves incident to a tortuous channel and the confusion of one sound wave with another is substantially eliminated.

In order to provide for the proper move-

ment of the arm 3 with respect to the record, I have devised a construction wherein the said arm is substantially balanced or maintained in equilibrium so that any movement 5 or movements which it may have due to irregularities in the record or otherwise are not reflected in the reproduced sounds in the form of scratching or scraping sound waves which mar or break up the quality 10 of the sound reproduced. In carrying out this embodiment of my invention, I have preferred to reversely bend or curve the sound arm 3, to form substantially a U-shaped portion and bring the delivery end thereof within the horn 1 in which position 15 it is supported upon a mechanism giving substantially the effect of a universal joint. This mechanism embodies a knife edge 7, fixedly carried by the arm 3 in any well known manner and adapted normally 20 to seat within a beveled slot 8, formed in the head 9 of a stud 10. It will be noted, however, that the slot 8 preferably does not extend the full width of the head 9, so that 25 a seat is formed which will prevent side or lateral movement of the knife edge 7. The head 9 of the stud 10 is also cut away on one side to form an angular face 11, which gives sufficient clearance on that side to 30 allow the arm 3 to swing on the knife edge 7, as a pivot, while swinging movement of the arm from one side to the other is permitted by mounting the stud 10 for rotation within a sleeve 12, the latter being suitably 35 fixed to the horn support 2. In order that vertical adjustment of the arm 3 may be made if desired, I preferably thread the stud 10 and employ a pair of nuts 13 located on opposite sides of the support 2, with respect to each other, and the action and operation will be readily apparent.

14 designates a lug or projection fixed to the arm 3, adjacent which and secured to the horn 1 is a spring catch 15, the latter being adapted at certain times to engage the lug 14, and thus lock the arm 3 in raised or inoperative position as shown in dotted lines, of Fig. 1. Attention is particularly directed to the cross sectional configuration 45 of both the arm 3 and horn 1, as thereby the sound is conveyed continuously and without interruption from the time it leaves the sound box until discharged from the horn 1, whereby the full sound quality is preserved and a substantially perfect reproduction 55 thereof attained.

In Fig. 7 I have shown another form of pivotal connection for the arm 3 to the support 2, in which the head 9 of the stud 60 10 is provided with a transverse annular channel 16 adapted to receive the pivot head 17 which is of the proper contour to permit the desired rocking movement. It will be noted that the pivotal support for the delivery end of the arm is located at such a

point that the vertical line passing therethrough will also pass through the center of gravity of the arm.

It will now be apparent that I have devised a complete unitary structure simple in 70 construction and effective in operation for reproducing in a perfect manner the sound-waves delivered from the sound box. It will further be seen that, having once adjusted the arm 3 with respect to the record, 75 there will be substantially no tendency to distort the sound arm and whatever pressure is transmitted from the record due to irregularities or the like, is at once taken up by the swing of the arm on its pivot.

Having thus described my invention, what I claim as new and desire to secure by Letters Patent, is:

1. In a talking machine, the combination 80 of a support, a tapered horn carried thereby, an amplifying arm having a reversely curved portion, a stud rotatably mounted in said support having a transverse channel therein, a pivot carried upon the under side of the upper terminal of said arm and seating in said channel, and a sound box carried by the lower terminal of said arm, said upper terminal extending a suitable distance 85 within said horn and freely movable therein.

2. In a talking machine, the combination 90 of a support, an amplifying arm having a reversely curved portion, one terminal thereof being in a horizontal plane above the horizontal plane of the other terminal, a sound box carried by the lower terminal of 95 said arm, a tapered horn stationarily supported and operatively positioned with respect to the upper terminal of said arm, and means carried by the said support and co-acting with said arm at a point adjacent the upper terminal of said arm to movably support said arm, said point being located in a vertical line passing through the center of gravity of said arm, whereby said arm is movable and is balanced in operative position.

3. In a talking machine, the combination 100 of a support, a tapered horn carried thereby, an amplifying arm having a reversely curved portion, a stud rotatably mounted in 105 said support having a transverse channel therein, a pivot carried upon the under side of the upper terminal of said arm and seating in said channel, the curve of said arm extending rearwardly of said pivot to form 110 a counterbalance for the lower terminal of said arm, which extends forwardly of said pivot, and a sound box carried by the lower terminal of said arm, said upper terminal being situated at a suitable point with respect to said horn and being freely movable 115 with respect thereto.

4. In a talking machine, an amplifying device comprising a tubular arm having a pair of opposed flat side walls and opposed 120

concave walls, said walls outwardly diverging, a sound box communicating with the end of said arm, and a horn suitably supported having opposed flat walls and opposed concave walls, the opposite end of said arm being operatively mounted with respect to said horn with the flat walls of each and the concave walls of each in jux-

taposed position forming a continuation thereof whereby the sound conduit is formed 10 without corners and is uniform in cross section throughout its extent.
